(57) **CLAIM**

The ornamental design for a daytime running light arrangement for a tail light, as shown and described.

DESCRIPTION

FIG. 1 is a front left elevated perspective view of a daytime running light arrangement for a tail light of a vehicle; FIG. 2 is a front left perspective view thereof;

FIG. 3 is a front view thereof;

FIG. 4 is a left side view thereof;

FIG. 5 is another front view thereof, but with the daytime running light arrangement mounted on a vehicle, and the rest of the vehicle shown in de-emphasized and half-tone portions to illustrate environmental structure. These portions form no part of the claimed design. More particularly, in FIG. 5, the daytime running light arrangement is shown within the broken line; and,

FIG. 6 shows an alternative embodiment, with the same daytime running light arrangement located on both sides of the unclaimed vehicle, as mirror images, thereby comprising an arrangement which includes a pair of daytime running lights.

In FIGS. 1-6, for visual clarity, a darker shade is used to show the activated, or illuminated, state of the tail light, in inverted fashion. This darker shade itself forms no part of the claimed design. Also, in these figures, the surrounding lighter tone portions are included for environmental purposes, and form no part of the claimed design.
